DESIGN FOR A CANDELABRA

Gretchen Goughnour, York, Pa., assignor to Lewis
P. Weil, Philadelphia, Pa.

Application March 8, 1938, Serial No. 75,656

Term of patent 3½ years

To all whom it may concern:

Be it known that I, Gretchen Goughnour, a citizen of the United States, residing in York, in the county of York, State of Pennsylvania, have invented a new, original, and ornamental Design for a Candelabra, of which the following is a specification, reference being had to the accompanying drawing forming part thereof.

Fig. 1 is a perspective view of a candelabra, showing my new design.

Fig. 2 is a plan view of same.

I claim:

The ornamental design for a candelabra, as shown.

GRETCHEN GOUGHNOUR.
